CLAIM

The ornamental design for a computer package, as shown and described.

DESCRIPTION

FIG. 1 is a top perspective view of a recyclable computer packaging, showing my new design, in a state of use;

FIG. 2 is a top perspective view thereof;

FIG. 3 is a top plan view thereof;

FIG. 4 is a bottom view thereof;

FIG. 5 is a right-side elevation view thereof;

FIG. 6 is a left side elevation view thereof;

FIG. 7 is a rear elevation view thereof; and,

FIG. 8 is a front elevation view thereof.

The broken lines in FIG. 1 depict environmental subject matter and form no part of the claimed design.

1 Claim, 6 Drawing Sheets(56)
